RADIO SHIELD FOR ENGINES

Roland Chilton, Ridgewood, N. J., assignor to
Wright Aeronautical Corporation, a corpora-
tion of New York

Application June 8, 1933. Serial No. 674,816

10 Claims. (Cl. 123—148)

This invention relates to improvements in radio shielding for engines, and more particularly, provides shielding means for use in conjunction with the magnetos of an aircraft internal combustion engine.

Radio shielding for engines broadly includes grounded metallic sheathing for all of the high tension elements of the ignition system, including the magneto distributors, high tension wiring and spark plugs. The particular phase of shielding with which this invention is concerned is that which covers the high tension wiring from the magnetos to the point or points whence the wires are led therefrom to the spark plugs of the individual cylinders.

Current types of aircraft engines to which shielding is applied, comprise a substantially circular crankcase having mounting lugs extending therefrom, which are bolted to a substantially circular mounting ring carried by the aircraft structure, the ring being of slightly larger diameter than the bolt circle of the mounting lugs; the ring and bolt circle are held to as small a diameter as possible to conserve space. The crankcase forward of the mounting lugs carries the engine cylinders, while, on the rear of the crankcase, rearward of the mounting ring and lugs, a plurality of engine accessories, including high tension magnetos for ignition, are grouped. It is essential that all, or nearly all, of such accessories be confined within a space having a diameter less than that of the mounting ring, in order that the engine may be removed or installed as a unit, without the necessity of removing certain accessories and reinstalling them after the engine has been mounted. This calls for careful arrangement of the engine accessories, and usually results in very small clearance between the crankcase, the accessories, and the mounting ring.

In the past, radio shielding for an engine as above outlined included forwardly facing metal elbows attached to the tops of the shielded magnetos, and from these elbows, trunk flexibly shielded cables extended forwardly, between the mounting ring and the crankcase, to divide and pass to the engine cylinders. Alternatively, the trunk cables have been connected to ring wire manifolds on the crankcase near the engine mount. This construction, due to the proximity of the front magneto face to the mounting ring, usually requires removal of the shielding elbows and cables from the magnetos to accomplish removal or installation of the engine. As the magnetos are usually adjustably rockably mounted

on the engine to allow for adjustment of spark timing, previous shielding installations have sometimes made necessary the movement of the magnetos from their properly adjusted positions in order to remove or install an engine. Obviously, this procedure is most inconvenient and expensive, as it subsequently requires retiming of the ignition and re-synchronizing of the two magnetos.

Since the engine carburetor is frequently mounted at the top of the crankcase, the ignition wire manifold must be interrupted on either side of the carburetor, and, since each of the engine cylinders is wired to each magneto, ignition wiring must be threaded from each magneto, around the carburetor, to each side of the ignition wire manifold. By the older construction, a neat shielding installation is difficult of accomplishment, flexible shielding must be used at points where the shielding may be damaged, and threading of the wiring, particularly in engines having a large number of cylinders, becomes increasingly difficult.

My invention provides a shielding arrangement wherein the ignition wiring is carried rearwardly from each magneto through a solid metallic conduit or manifold, the latter being provided with a crossover between the magnetos rearward of the engine mounting ring, so that solid trunk manifolds may be led to each side of the engine to contain only those ignition wires which terminate at the cylinders on those respective sides of the engine. By the rigid mounting of the crossover conduit with relation to the engine crankcase, and by the provision of telescoping joints between the crossover conduit and the magnetos, individual timing adjustment of the magnetos may be effected without affecting the balance of the shielding and wiring and without affecting the ease with which the engine may be mounted or dismounted. Further, the solid manifolds and conduits are sturdy and resistant to abrasion which might occur by careless handling of the engine. My construction also permits relatively easy replacement of wiring, since all wiring is carried in the crossover element and the trunk manifolds from the magnetos to those points in the manifolds whence the individual wires are led to the engine cylinders.

Objects of the invention are to provide an improved shielding for engines; to provide solid shielding manifolds mounted on the engine; to provide means for allowing magneto timing adjustment without interfering with engine removal or the shielding elements; and to provide a

radio shielding manifold attached to and forming a part of the engine, whereby removal of all or part thereof is unnecessary in mounting or dismounting the engine from an aircraft. It will be apparent that the principles of my invention may be embodied in shielding for other types of engines, such as V type or in-line type.

Further objects will be apparent in reading the specification and claims, and in considering the drawing, in which Fig. 1 is a plan of the rearward portion of an engine crankcase carrying the shielding of this invention, and Fig. 2 is a rear elevation of the same structure.

The rear crankcase section 10 of an engine, of substantially circular shape, projects rearwardly through an engine mounting ring 11. Lugs 12 extending outward from the crankcase, bridge the space between the case and the ring, and are adapted to be attached thereto by clips 13 encircling the ring tubing, the bolts 14 passing through the clips and lugs. On the rear face of the crankcase 10, a pair of magnetos 15 are mounted for angular adjustment, by means of studs 16 engaging slotted openings 17 in the magneto flanges 18. Each magneto is provided with a metallic distributor shield 19 having a rearward opening 20 within which an elbow 21 is fitted for slight angular adjustment. A crossover conduit 22 is provided with oppositely facing inlets 23 adapted to telescopically engage the open ends of the elbows 21. Packing nuts 24 are provided to effect a snug joint between the conduit 22 and the elbows 21. The conduit 22 is held rigidly on the crankcase 10, the telescopic joints between the conduit 22 and the elbows 21 allowing for individual timing adjustment of the magnetos 15 without affecting the position of the conduit. Forwardly extending angular outlets 25 on the conduit 22 connect with conduits 26, by suitable joints 27, said conduits 26 extending forwardly, around a carburetor 28, to be connected as at 29 to shielded manifolds 30 which partly encircle the crankcase 10 beneath the mounting lugs 12. The manifolds 30 are provided with a plurality of outlets 31, conveniently spaced, through which individual wires may pass to the engine cylinders. An example of the wiring is indicated wherein a wire 34 passes from the left magneto, and a wire 35 passes from the right magneto, through the conduit 22, and thence through the left hand outlet 25, the left hand conduit 26, the left hand manifold 30, through a pair of outlets 31 to one of the left hand engine cylinders. Similarly, wires 36 and 37 pass, one from each magneto, through the right hand manifold system to a right hand cylinder. Thus, only those wires for right hand cylinders lead from the right hand outlet of the crossover conduit 22, and only wires for left hand cylinders lead from the left hand outlet of the crossover conduit 22. The wiring is greatly simplified over the old system, avoiding sharp bends and allowing all elements to be firmly anchored to the engine.

By the use of the rigid manifolds 26, a fixed clearance distance X is allowed between them and the mounting ring 11, which clearance, in previous structures either did not exist or was subject to variation when the magnetos were adjusted through the angle Y , since the manifolds moved with the magnetos.

While I have described my invention in detail in its present preferred embodiment, it will be obvious to those skilled in the art, after understanding my invention, that various changes and

modifications may be made therein without departing from the spirit or scope thereof. I aim in the appended claims to cover all such modifications and changes.

What is claimed is:

1. A radio shielding for an engine having angularly adjustable magnetos comprising a wire encasing manifold, a crossover wire encasing connection telescopically connecting said magnetos, and shielding conduits connecting said crossover connection to said manifold. 80
2. The combination with an engine having shielded magnetos mounted for timing adjustment of a telescopic cross over ignition wire shield connecting said magneto shields. 85
3. The combination with an engine having shielded magnetos mounted for timing adjustment, of a telescopic crossover ignition wire shield connecting said magneto shields, said telescopic crossover shield having outlets, and shielding conduits connecting to said outlets. 90
4. The combination with an engine having rockably mounted shielded magnetos, of a twin outlet crossover shielding telescopically connected with said magneto shields, and shielding conduits connected to said crossover connection, the whole adapted for adjusting movement of said magnetos without movement of said connection or conduits. 95
5. The combination with an engine having movably mounted magnetos provided with radio shields, of a rigid crossover connection telescopically connecting the magneto shields and provided with suitable outlets and shielding conduits connecting said outlets. 100
6. The combination with a radial cylinder engine having a pair of oscillatable magnetos mounted on the rearward end thereof, of a shielding conduit fixed to the engine, and members movably carried on said magnetos and adapted to telescope within said conduit, said members and conduit being adapted to house the wiring emanating from said magnetos. 110
7. The combination with a multi-cylinder engine having a pair of oscillatable magnetos mounted thereon in spaced relation, of a metallic shielding conduit mounted on said engine, said conduit having an opening adjacent each magneto, and hollow members carried by each magneto and telescopically engageable with said conduit to permit adjustment of said magnetos with respect to said engine and conduit, said members and conduit being adapted for the housing of ignition wiring. 120
8. The combination with a multi-cylinder engine having a magneto mounted for limited angular adjustment on said engine, of an elbow carried by said magneto and a metallic shielding conduit mounted on said engine, said elbow and conduit being arranged for telescopic engagement to permit relative adjustment therebetween, and said elbow and conduit being adapted for the housing of ignition wiring. 130
9. The combination with an engine having a crankcase adapted to be carried by a mounting ring, wherein said ring is in substantially angularly spaced relation to said case and wherein a magneto is carried for angular adjustment on said crankcase, of a metallic radio shielding conduit mounted on said case and passing between said ring and said case, said conduit having a movable shielding connection with said magneto to permit adjustment of said magneto relative to said conduit. 140
10. The combination with a multi-cylinder en- 150

gine having a pair of magnetos mounted thereon, of radio shielding means comprising an elbow mounted on each magneto, a substantially straight conduit connecting said elbows, said conduit having a pair of central angled openings, and a pair of metallic shielding manifolds registering with said angled openings, each said

manifold being adapted to house ignition wiring from both said magnetos, and each said manifold having spaced openings through which wiring from both said magnetos may pass to the several engine cylinders.
